UNITED STATES PATENT OFFICE.

CHARLES L. GRANGER, OF DETROIT, MICHIGAN, ASSIGNOR TO THE COMMERCE MOTOR CAR COMPANY, OF DETROIT, MICHIGAN, A CORPORATION OF MICHIGAN.

DESIGN FOR A RADIATOR-CASING.

53,413.

Specification for Design.

Patented June 10, 1919.

Application filed March 7, 1918. Serial No. 221,076. Term of patent 14 years.

To all whom it may concern:

Be it known that I, CHARLES L. GRANGER, a citizen of the United States of America, residing at Detroit, in the county of Wayne and State of Michigan, have invented a certain new, original, and ornamental Design for a Radiator-Casing, of which the following is a specification, reference being had therein to the accompanying drawings, forming part thereof, in which—

Figure 1 is a front elevation of a radiator casing, showing my new design, and Fig. 2 is a side elevation of the same.

I claim:

The ornamental design for a radiator casing, substantially as shown.

CHAS. L. GRANGER.
